US00D868366S

(12) **United States Design Patent** (10) **Patent No.:** **US D868,366 S**
(45) **Date of Patent:** **** Nov. 26, 2019**

(54) **ELECTRONIC VAPOR DEVICE**

- (71) Applicant: **Altria Client Services LLC**,
Richmond, VA (US)
- (72) Inventors: **Eric Hawes**, Midlothian, VA (US);
Raymond Lau, Richmond, VA (US);
Ben Sharp, Cambridge (GB)
- (73) Assignee: **Altria Client Services LLC**,
Richmond, VA (US)
- (**) Term: **15 Years**
- (21) Appl. No.: **29/574,186**
- (22) Filed: **Aug. 12, 2016**

Related U.S. Application Data

- (63) Continuation-in-part of application No. 14/998,040,
filed on Apr. 22, 2015.
- (51) **LOC (12) Cl.** **27-06**
(52) **U.S. Cl.**
USPC **D27/162**
- (58) **Field of Classification Search**
USPC D27/100, 101, 139–161, 162–196;
D24/110; D23/366; D3/273; D9/455,
D9/456
CPC A24F 15/00; A24F 9/16; A24F 47/002;
A24F 1/00
See application file for complete search history.

(57) **CLAIM**

The ornamental design for electronic vapor device, as shown and described.

DESCRIPTION

FIG. 1 is a top view of an electronic vapor device including a pre-sealed cartridge;
FIG. 2 is a bottom view of the electronic vapor device of FIG. 1;
FIG. 3 is a front view of the electronic vapor device of FIG. 1;
FIG. 4 is a back elevation view of the electronic vapor device of FIG. 1;
FIG. 5 is a left side view of the electronic vapor device of FIG. 1;
FIG. 6 is a right side view of the electronic vapor device of FIG. 1;
FIG. 7 is a top perspective view of the electronic vapor device of FIG. 1; and,
FIG. 8 is a bottom perspective view of the electronic vapor device of FIG. 1.

The portions of the design shown in broken lines form no part of the claimed design.

1 Claim, 6 Drawing Sheets
